CONTAINER LABELING MECHANISM

Charles Schmutzler, Irvington, N. J., assignor to
Hoffman Beverage Company, Newark, N. J., a
corporation of New Jersey

Application December 31, 1936, Serial No. 118,446

17 Claims. (Cl. 216—54)

This invention relates to container labeling machines, and has particular reference to means for stabilizing the movement of the label picker in transferring a label from the label magazine to the container to be labeled.

In a conventional form of labeling machine, upon which the present invention is an improvement, the picker is splined on a shaft which is oscillated about its longitudinal axis by a cam to advance and retract the picker to and from the label magazine and to and from the container, the picker being alternately reciprocated between the label magazine and the path of movement of the container by means of a second cam so that the picker describes a generally U-shaped course, viz: backwardly from the label magazine, from which its gummed surface abstracts a label, across to the container-carrying table and forwardly to lay the label on the container where it is held by a finger until applied. The picker is suspended from the oscillating shaft and the spline thereof is relied on to impart the oscillating movement to the picker. Because the spline must afford free movement of the picker along the oscillating shaft, there is a certain degree of looseness in the spline which increases as the spline wears, and so, though the picker is light in weight, it vibrates as its direction of motion changes during its U-shaped course of travel to a degree that frequently results in a continuous and sustained chattering causing disarrangement of the label thereon, both because of the jar of the vibration and because of the air currents induced by the vibration, resulting in misalignment of the label on the container.

Also, excessive chattering of the picker because of the aforementioned reasons, not infrequently results in fouling between the picker and the label grip finger, which moves into engagement with the label in the container as the picker retracts after having laid the label. These conditions become aggravated as the speed of the labeling operation is increased, so that the machine frequently cannot operate at a rate conforming to other concomitant operations, such as filling, sealing and the like, resulting in a slowing down of an entire manufacturing process.

In accordance with the present invention, means are provided for stabilizing the movements of the picker of a container labeling machine of the form described, whereby vibration of the picker due to the aforementioned causes is minimized, permitting operation of the labeling machine at high speed without liability of mis-

alignment of the labels on the containers because of vibration.

In the preferred embodiment of the invention, which may be readily applied to existing labeling machines without material change thereof, the splined connection between the picker and the oscillating shaft is eliminated, so that the latter acts merely as a guide along which the picker reciprocates, and a brace bar is positioned parallel to the shaft as a second guide for the picker, this brace bar being rigidly connected to the shaft by end clamps operatively connected to the cam so that the shaft and brace bar are oscillated as a unit by the cam about the axis of the shaft. With this arrangement the leverage of the angular connection between the shaft and the picker is greatly increased by the difference between the relatively short radial length of the former spline and the spacing between the axis of the shaft and the brace bar.

It will be seen that with the arrangement of the present invention, a firm, positive connection between the picker and its actuating support is provided which is devoid of looseness, such as that required in the spline between picker and the shaft in the former arrangement to permit free movement of the picker, whereby a firm, positive movement is imparted to the picker throughout its U-shaped course of travel, regardless of the speed at which it is moved within the speed capacity of the labeling machine.

In a more complete understanding of the invention reference may be had to the accompanying drawings, in which:

Figure 1 is a side elevation of a label picker mechanism embodying the stabilizing means of this invention;

Figure 2 is a rear elevation thereof;

Figure 3 is a front elevation thereof;

Figure 4 is an enlarged section through the oscillating shaft and guide bar, as seen along the line 4—4 of Fig. 3;

Figure 5 is a similar section as seen along the line 5—5 of Figure 3; and

Figure 6 is a fragmentary plan view of the labeling machine equipped with the stabilized picker of this invention.

Referring to Fig. 6 of the drawings, numeral 12 designates the rotating table of a conventional form of a container labeling machine particularly arranged to label bottles such as beverage bottles. By mechanism which is well understood and therefore not described herein, the bottles B are placed on the table 10 and held in position by a cam-operated clamp 11 which descends 55

and engages the cap of the bottle to hold it firmly on the table 10. Positioned adjacent the rotating table 10 is a body label magazine 12 with which a picker, generally designated 13, operates to transfer gummed body labels, one by one, into the path of the movement of the bottles B. The picker is bifurcated and the bottle passes through the space between the arms of the picker to abstract the label spanning this space. A cam-actuated label-holding finger 14 moves into engagement with the label as the picker moves away after having laid the label on the surface of the bottle. The labels are then adhered to the surface of the bottle by suitable label-wiping means, not shown. Also positioned adjacent the table 10 may be a neck label magazine 12' with which cooperates a similar picker 13' in the manner described.

The pickers 13 and 13' are suitably supported on a frame 15 extending over the rotating table 10 as indicated particularly in Figs. 1, 2 and 3. Journalled in the frame 15 is a horizontal shaft 16, which, according to the present invention has secured to its opposite ends, by means of keys 17 and clamping bolts 18, a pair of end clamps 19. Rigidly secured between the free ends of end clamps 19 is a bar 20 preferably rectangular in cross-section and provided with a longitudinal lightening groove 21. The shaft 16 and bar 20 are accordingly secured together in fixed spaced relation and may move as a unit about the axis of the shaft 16 as the latter oscillates.

The left hand end clamp 19 as seen in Fig. 3 is provided with a lateral extension 21 to which is pivoted the link 22 adjustable as to length by the turn buckle 23 and pivoted at its lower end to the free end of the bell crank 24 suitably journalled on the frame of the machine at 25. The opposite end of the bell crank 24 is fitted with a roller 26 running in the groove 27 of the cam 28 mounted on shaft 29 and rotated by the same means which drives the machine so that it rotates in synchronism with the remaining parts of the labeling machine. By means of this cam 27 the shaft 16 and bar 20 are oscillated about the axis of shaft 16.

Slidably mounted jointly on the shaft 16 and the bar 20 is the picker slide 30. As shown particularly in Fig. 5, bushings 31 are interposed between the slide 30 and the bar 20 and are adjustable by means of set screws 32 to secure a free running fit between the picker slide 30 and the bar 20 without looseness. Formed on the picker slide 30 is a downwardly-extending double arm bracket 33, to the two arms of which are secured by means of bolts 34 and keys 35 the two arms 36 of the picker 13, which are spaced apart and shaped to accommodate the bottle B between them. The picker arms 36 are fitted with picker plates 37 and/or 38, the former being for the body label B₁ and the latter for the neck label N₁, both indicated in Fig. 3. The picker arms 36 are preferably provided with both body label and neck label plates 37 and 38 so as to be interchangeable for body label and neck label service.

The picker slide 30 is provided with a lateral extension 39 having a socket in its rear surface into which is loosely fitted a pin 40 mounted on the free end of the reciprocating cam arm 41, which is pivoted at its lower end at 42 on the frame of the machine and is provided intermediate its ends with a roller 43 moving in the groove 44 of cam 45 secured to shaft 29, as shown particularly in Figs. 1 and 2. Buffer springs 46 are mounted on the opposite ends of the circular

portion of bar 20 between a fixed collar 47 and an inside sliding collar 48 for buffering the movement of the picker slide 30 on the bar 20 at its opposite ends of travel as it is oscillated along the shaft 16 and bar 20 by means of lever 41 as the latter is moved by cam 45.

In operation, the movements imparted to the picker slide 30 in oscillation about the axis of shaft 16 and in reciprocation along shaft 16 and bar 20 are synchronized by cams 28 and 45 in such a way that the picker 13, including the two arms 36, is moved against the outermost label in the body label magazine 12 after the plates 37 have been gummed in the usual way by the gum roller, not shown. The label adheres to the picker 13, including the two arms 36, and is extracted from the magazine 12. The rearward movement of the picker 13, caused by the tilting of the shaft 16 and bar 20 by cam 28, is followed by the longitudinal movement of the picker slide 30 along the shaft 16 and bar 20 by the action of cam 45.

The label is thus placed over the table 10 in the path of the advancing bottle B, so that as the picker 13 advances with the bottle due to the action of the cam 28 to complete the U-shaped course of the picker, the label is laid on the bottle B and at once the label holding finger 14 moves into engagement with the label to hold it in place on the bottle in accordance with the usual operation of the machine. Cam 28 then reverses the movement of the picker 13 and cam 45 returns the latter along the bar 20 and shaft 16 to its position opposite the label magazine 12, whereupon cam 28 again comes into action to move the picker 13 into engagement with the label stack in magazine 12 to repeat the cycle of operation just described.

It will be observed that, though the center of oscillation of the picker 13 is about the axis of the shaft 16, the leverage securing this movement extends from the center line of shaft 16 to the bar 20, a considerable distance as is shown in Fig. 5. Because of this considerable leverage the movement of the picker 13 is firm and positive. Also, the adjustment of the bushings 31 on the bar 20 affords a minimum clearance consistent with a free running fit, so that there is no looseness to cause vibration of the picker 13.

Thus, even at high operating speeds, the movement of the picker is smooth, firm, and positive, and the chattering of the picker that takes place in the former machines is entirely eliminated. Accordingly there is no disarrangement of the label on the picker and consequently no misalignment of the label on the bottle due to vibration or to air drafts induced by vibration or chattering. Because there is no chattering of the picker, it cannot foul the label holding finger 14 which moves up within the range of any large vibration of the picker as the latter lays the label on the bottle.

The neck label picker 13' cooperating with the neck label magazine 12' is also provided with the brace bar arrangement and its operation is precisely the same save only that the neck labels N₁ are positioned on the neck label plates 38 of the picker for application to the neck of the bottles as the bottle moves relatively between the two arms 36 of the neck label picker 13'.

Although the picker stabilizing mechanism of this invention has been illustrated and described in connection with a particular form of container labeling mechanism, it is to be understood that it is applicable with equal facility to other container labeling machines and the like.

I claim:

1. In a label picker mechanism having a picker reciprocating laterally along an oscillating shaft, the combination of means for stabilizing the movement of the picker including a guide substantially parallel to said shaft and oscillating therewith, and a connection between said picker and said guide, whereby the picker reciprocates jointly along said shaft and guide.
2. In a label picker mechanism having a picker reciprocating laterally along an oscillating shaft, the combination of means for stabilizing the movement of the picker including a guide rigidly secured in parallel spaced relation to said shaft and oscillating therewith, and a slide on the shaft rigidly connected to said picker whereby the picker reciprocates jointly along said shaft and guide.
3. In a label picker mechanism having a picker reciprocating laterally along an oscillating shaft, the combination of means for stabilizing the movement of the picker including a guide rigidly secured in substantially parallel spaced relation to said shaft and oscillating therewith, a member movable along said guide, and rigid connections between said picker and said member, whereby the picker reciprocates jointly along said shaft and guide.
4. In a label picker mechanism having a picker reciprocating laterally along an oscillating shaft, the combination of means for stabilizing the movement of the picker including members spaced longitudinally of the shaft and oscillating therewith, a guide carried by said members in substantially parallel spaced relation to said shaft, and an extension on the picker engaging said guide for movement therealong as the picker reciprocates.
5. In a label picker mechanism having a picker reciprocating laterally along an oscillating shaft, the combination of means for stabilizing the movement of the picker including members rigidly secured to the shaft adjacent its ends for oscillation therewith, a guide rigidly secured to said members in substantially parallel spaced relation to said shaft and oscillating therewith, and a rigid extension on said picker engaging said guide for movement therealong as the picker reciprocates.
6. In a label picker mechanism having a picker reciprocating laterally along an oscillating shaft, the combination of means for stabilizing the movement of the picker including members rigidly secured in spaced relation longitudinally of said shaft, a guide carried thereby and extending in substantially parallel spaced relation to said shaft, a slide thereon, and a rigid connection between said picker and said slide.
7. In a labeling machine having a label picker, the combination of a support, a pair of substantially parallel spaced guides thereon, means for jointly oscillating said guides about an axis substantially parallel thereto, a slide on said guides fixedly carrying said picker for oscillation with said guides, and means for reciprocating said slide along said guides during said oscillation of said guides, slide, and picker.
8. In a labeling machine having a label picker, the combination of a support, a pair of substantially parallel spaced guides thereon, means for jointly oscillating one of said guides about the longitudinal axis of the other guide, a slide on said guides fixedly carrying said picker for oscillation with said guides, and means for recip-

rocating said slide along said guides during said oscillation of said guides, slide, and picker.

9. In a labeling machine having a label picker, the combination of a support, a pair of substantially parallel spaced guides thereon, means for jointly oscillating said guides about the longitudinal axis of one of them, a slide on said guides fixedly carrying said picker for oscillation with said guides, and means for reciprocating said slide along said guides during said oscillation of said guides, slide, and picker.

10. In a labeling machine having a label picker, the combination of a support, an elongated guide thereon, spaced members pivoted about an axis substantially parallel to said guide, a second guide carried by said members in substantially parallel spaced relation to said first guide, means for oscillating said members and said second guide about said axis, a slide on said guides carrying said picker, and means for moving said slide along said guides as the latter oscillate about said axis.

11. In a labeling machine having a label picker, the combination of a support, an elongated guide thereon, a second elongated guide supported for parallel movement about the longitudinal axis of said first guide, a slide on said first guide having a lateral extension embracing said second guide, means for oscillating said second guide about said axis, means for reciprocating said slide along said guides, and means for adjusting the degree of contact between said slide and said second guide.

12. In a labeling machine having a label picker, the combination of a support, an elongated guide thereon, a second elongated guide supported for parallel movement about the longitudinal axis of said first guide, a slide on said first guide having a lateral extension embracing said second guide, means for oscillating said second guide about said axis, means for reciprocating said slide along said guides, and an adjustable bushing between said extension and said second guide.

13. In a labeling machine having a label picker, the combination of a support, an elongated guide thereon, spaced members pivoted about the longitudinal axis of said guide, a second elongated guide carried by said members in substantially parallel spaced relation to said first guide, means for oscillating said members and second guide about said axis, a slide on said guides carrying said picker, and means for reciprocating said slide along said guides as the picker oscillates about said axis.

14. In a labeling machine having a label picker, the combination of a support, an elongated guide thereon, spaced members secured to said guide, said guide and members being pivoted on the support, a second guide secured to said members in rigid spaced, substantially parallel relation with respect to said first guide, means for oscillating said members and guides about said pivot, a slide on said guides carrying the picker, and means for reciprocating said slide along said guides as the picker oscillates.

15. In a labeling machine having a label picker, the combination of a support, a shaft journaled thereon, a slide carrying the picker movable along said shaft, means for reciprocating said slide along said shaft, end clamps secured to said shaft, a guide bar rigidly secured to said end clamps in spaced substantially parallel relation to said shaft, an extension on said slide embracing said guide bar, and means for oscillating said shaft, end clamps, guide bar, slide and picker about the axis of said shaft.

16. In a labeling machine having a label picker, the combination of a support, a shaft journaled thereon, a slide carrying the picker movable along said shaft, means for reciprocating said slide along said shaft, end clamps secured to said shaft, a guide bar rigidly secured to said end clamps in spaced substantially parallel relation to said shaft, an extension on said slide embracing said guide bar, means for oscillating said shaft, end clamps, guide bar, slide and picker about the axis of said shaft, an elongated bushing interposed between said slide extension and said guide bar, and means for adjusting the bushing to vary the degree of tightness between the slide and said 10 guide bar.

17. In a labeling machine having a label picker, the combination of a support, a shaft journaled thereon, a slide carrying the picker movable along said shaft, means for reciprocating said slide along said shaft, end clamps secured to said shaft, a guide bar rigidly secured to said end clamps in spaced substantially parallel relation to said shaft, an extension on said slide embracing said guide bar, means for oscillating said shaft, end clamps, guide bar, slide and picker about the axis of said shaft, and buffer means at the ends of said guide bar for engagement by said slide at the extremities of its reciprocating movement.

CHARLES SCHMUTZER. 15
